UNITED STATES PATENT OFFICE.

WILBUR WALTERSON HENRY, OF OSWEGO, KANSAS.

MOUNTING OR ADAPTING TRACTORS TO DRILL RIGS.

Application filed January 2, 1926. Serial No. 79,014.

This invention relates to mounting or adapting a tractor to a drill rig.

The object of the invention is the provision of simple and efficient means for coupling up a motor or engine to a drill rig.

Another object of the invention is the construction of a simple and efficient frame which includes means for receiving an engine or motor, together with means for operating a drill rig, all being efficiently assembled on a wheeled frame, of a tractor type.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in side elevation of an apparatus constructed in accordance with the present invention, while

Figure 2 is a top plan view of the same.

Figure 3 is a view in front elevation of the apparatus.

Figure 4 is a sectional view taken on line 4—4, Figure 2, and looking in the direction of the arrows.

Figure 5 is a fragmentary perspective view of the gear shifting device.

Figure 6 is a sectional view of the stuffing box for the transverse driving shaft.

Referring to the drawings by numerals, 1 designates the frame which is mounted in any conventional way upon wheels, and this frame includes front vertical standards 2; rear vertical standards 3; central vertical standards 4 and intermediate vertical standards 5. A pair of horizontal, longitudinally extending beams 6 connect the tops of standards 3 and 5 and are secured at their inner ends to central standard 4. Short standards 7 are fastened at their lower ends to beams 6 and inclined braces 8 are connected at their upper ends to standards 7 and these braces are also fastened to beams 6, central standard 4 and the base part of the frame 1, for bracing the entire structure. Fastened to the sides of the short standards 7 are angle brackets 9; these brackets 9 have their upper ends extending outwardly, upon which is detachably mounted the inclined braces 10 of the derrick structure hereinafter described. Bracing rods 11 are secured at one

end, in any suitable manner, to central standards 4 and at their opposite ends are secured to plates 12 which plates are fastened to the top of standards 7.

In the compartment A formed upon the frame between the base thereof and standards 3 and 5 and beams 6 is positioned the motor 13. This motor or engine can be of any suitable type, and is provided with a driving shaft 14, which shaft and motor is positioned transversely of the frame for easily adapting the motor to this wheeled or tractor drilling apparatus.

Formed upon the motor 13 is a stuffing box 15 (Fig. 6) which comprises an inner cup-like plate section 16, which section 16 carries suitable packing for making a tight joint around the shaft 14. A plug 17 is in the outer end of section 16 against the packing therein, and mounted upon shaft 14 and surrounding the outer end of section 16 is a threaded cap 18 which screws upon section 16, as clearly shown in Figure 6.

The driving shaft 14 is provided with a sprocket wheel 19 around which is positioned sprocket chain 20, and this sprocket chain 20 is also passed around sprocket wheel 21, which sprocket wheel is fixedly secured to shaft 22. Shaft 22 is mounted upon the frame in any ordinary manner, and secured to shaft 22 is sprocket wheel 23. Mounted upon sprocket wheel 23 is sprocket chain 24, which chain 24 is mounted upon sprocket wheel 25, and this sprocket wheel 25 is secured to shaft 26 (Fig. 2). Shaft 26 carries at its ends, cogs 27, which cogs mesh with the gears 28 that are attached to the tractor-wheel 29, whereby the entire apparatus can be driven over the ground by the motor mounted on the frame.

At the front of the frame is a throttle pulley wheel 30 around which passes throttle cable 31. The ends of throttle cable 31 are connected to the manipulating device 32 of the carburetor 33 (Fig. 4), so that at the front of the machine the control of the carburetor or the "throttling" of the motor can be accurately obtained.

Hand operated lever 34 is pivotally mounted upon the frame at 35 (Fig. 5) and the upper end of this lever 35 is connected to link 36, which link 36 is pivotally connected to bell crank lever 37 and this bell crank lever is pivotally connected to link 38 and link 38 is also connected to arm 39.

The arm 39 is fixedly secured to gear rod 40, and the rear end of gear rod 40 is connected in any ordinary manner to the gear shifting means 41 of the motor 13, whereby 5 the operator can obtain three speeds forward and one reverse for drill tools and for transporting the rig.

I provide a clutch lever 42 that is pivotally mounted at 43 upon the frame and the 10 upper end of the lever 42 is pivotally connected at 44 to the outer end of clutch rod 45. The inner end of clutch rod 45 is pivotally connected to transverse clutch rod 46 (Fig. 2) and on this rod 46 is a clutch 15 pedal 47. Suitable means 48 connect rod 46 and the clutch mechanism of motor 13 whereby when the operator manipulates the clutch lever 42 or clutch pedal 47 the clutch of the motor will be operated for the desired 20 purpose and in the usual manner. It will, therefore, be seen that I have provided at the forward end of the apparatus, simple and efficient means for controlling the throttle of the motor, its gear shift, and also the 25 clutch thereof.

The derrick device comprises two main uprights 49 that are hingedly mounted at 50 upon the upper ends of the forward standards 2, whereby these uprights 49 can be folded down upon the frame as shown 30 in dotted lines (Fig. 1) when it is desired to have the apparatus travel from one place to another. The braces 10 are provided at their upper ends with plates 51, and these 35 plates 51 are detachably fastened at 52 to the sides of the uprights 49. By detaching the plates 51 from the uprights 49, the braces can be laid down on the frame as shown in 40 dotted lines Figure 1. Each brace 10 is provided with a plurality of apertures 53, through which any suitable fastening means may be placed for adjustably mounting the braces upon the upper end of the angle brackets 9. A pulley wheel 54 is mounted 45 upon brackets 55 (Fig. 3) and these brackets 55 are secured to a cross piece 56; cross piece 56 is fastened to the upper ends of uprights 49. Passing over or partly around pulley 54 is drill cable 57; the outer end of cable 57 is fastened to drill rod 58. Cable 57 is passed under pulley 59; pulley 59 is journalled upon transverse piece 60, which piece 60 is secured to the top of beams 61. These beams 61 are a part of the oscillating 55 device which oscillates or swings upon the pivot shaft 62 for operating the drill rod 58, giving a reciprocal movement to the rod. Cable 57 also passes over pulley 63, carried by shaft 62, and the cable is wound around drum 64, in an ordinary manner. Pitman rods 65 are pivotally connected at their upper ends to the under face of the oscillating 60 beams 61, and the lower end of one of these rods (Fig. 3) is pivotally connected to the rotatable arm 66, which arm 66 is suitably 65

connected to ordinary gear for operating the same. The other pitman rod 65, at the right side of the machine (Fig. 3) is connected to a lug or stub shaft 67 on gear 68, whereby an oscillating or swinging movement in a vertical plane, of beams 61 is accomplished for raising and lowering the drill rod 58.

A drill tool lifting cable 69 is provided, which is wound around drum 70 and this 75 drum 70 is rotated, when desired, in any ordinary manner for permitting cable 69 to be used to lift the drill rod or drilling tools as desired.

On the driving shaft 14 is a belt wheel 71 80 that can be used for any kind of work such as in operating a pump.

The belt 72 is utilized on belt wheels 73 and 74 for driving the shaft 75 upon which 85 is mounted said drum 70.

It is to be understood from the foregoing that I have invented a strong and efficient frame structure that supports the motor or engine, preferably one commonly known as the "Fordson" tractor, and my frame is furnished with means for efficiently connecting the motor or engine to a drill rig.

The operator of the apparatus stands (or he is positioned) near the standards 2 in convenient reach of the operating levers of 95 the gear and clutch mechanisms, as well as within reach of the throttle cable 31, whereby the entire apparatus is efficiently under the control of one operator.

It is also to be understood that the driving 100 shaft 14 is suitably connected to the transmission of an ordinary motor. This shaft 14 enables the drive to be made from the rear of a motor, with the motor in transverse position upon the frame, the shaft extending a considerable distance beyond one side of the frame for more efficiently accommodating the hook up with the other elements of the drilling apparatus.

While I have described the preferred embodiment of my invention and illustrated the same in the accompanying drawings, certain minor changes or alterations may appear to one skilled in the art to which this invention relates during the extensive manufacture of the same and I, therefore, reserve the right to make such alterations or changes as shall fairly fall within the scope of the appended claims.

What I claim is:

1. In an apparatus of the class described, the combination of a wheeled tractor frame including a plurality of contiguous uprights, horizontal beams fastened to the top of said uprights, said uprights and horizontal beams forming a compartment on said frame, a motor in said compartment between some of said uprights and provided with a shaft projecting beyond one side of the frame, and means connected to said shaft beyond 125 130

the side of the frame for either operating the tractor wheels or drilling means carried at the front of said frame.

2. In an apparatus of the class described, 5 the combination of a wheeled tractor frame provided with sets of uprights at the rear end thereof, said uprights producing a motor receiving compartment upon said frame, a motor on said frame between the sets of 10 uprights within said compartment, drilling means on the forward end of said frame, and means extending out of said compartment and connected to said motor whereby the 15 motor may be manipulated for driving the frame over the ground.

3. In an apparatus of the class described, 20 the combination of a frame provided with forward standards and with central standards, a pair of substantially horizontal beams pivotally mounted at their inner ends upon said central standards, a pulley supported upon said forward standards, a transverse piece on said beams, a pulley supported 25 upon said transverse piece, a pulley

contiguous to the inner ends of said beams and said central standards, a drum carried by said frame, a drilling tool contiguous to said forward standards, a cable fastened to said drilling tool and passing partly around 30 all of said pulleys and wound upon said drum, and means for raising and lowering the outer ends of said beams for operating said drilling tool through said cable.

4. In an apparatus of the class described, 35 the combination with a frame, of standards on said frame, horizontal beams connecting some of said standards, short standards fastened to said horizontal beams, brackets fastened to said short standards, plates secured 40 to the top of said short standards, brace rods secured at one end to said plates and at their opposite ends to some of said standards, hingedly mounted uprights on some of said standards, and adjustable braces connected to said hingedly mounted uprights 45 and to said brackets.

In testimony whereof I hereunto affix my signature.

WILBUR WALTERSON HENRY.
